BASIC ETHERS OF ACRIDONES AND THIAXANTHONES

Norbert Steiger, Nutley, N. J., assignor to Hoffmann-La Roche Inc., Nutley, N. J., a corporation of New Jersey

No Drawing. Application February 8, 1955,
Serial No. 486,983

9 Claims. (Cl. 260—279)

This invention relates to certain tricyclic heterocycles having a single heterocyclic nitrogen or sulfur atom. More particularly, the invention relates to basically substituted acridones and thiaxanthones.

The compounds of this invention can be characterized as comprising, respectively, the 9(10H)-acridone nucleus of Formula I below and the 10-thiaxanthone nucleus of Formula II below wherein each of said nuclei is substituted by at least one basic ether radical and at least one halogen as later defined herein.

The numbering systems employed to identify the compounds of this invention correspond to the preferred numbering systems indicated in "The Ring Index" by Patterson and Capell (New York, 1940) for the structurally related acridine and thiaxanthene under Numbers 1973 and 2019, respectively. It will be observed that the numbering plan for the thiaxanthone nucleus differs somewhat from that for the acridone nucleus in agreement with the preferred numbering systems employed by "The Ring Index."

In particular, the invention relates to compounds selected from the class consisting of bases having the formula

wherein Z is a bivalent radical selected from the group consisting of imino and thio, and each R is a monovalent radical selected from the group consisting of hydrogen, halogen, lower alkyl and di(lower alkyl)-amino-(lower alkoxy); at least one, but not more than two, of the radicals R being a di(lower alkyl)-amino-(lower alkoxy) radical and at least one, but not more than two additional, of the radicals R being a halogen atom and salts of said bases.

In the compounds of the invention represented by Formula III above, at least one, but not more than two, of the radicals R attached to the nuclear carbon atoms of the aromatic rings is a di(lower alkyl)-amino-(lower alkoxy) radical, e. g. dimethylaminomethoxy, dimethylaminooethoxy, diethylaminooethoxy, dimethylaminopropoxy, diethylaminopropoxy, and the like. At least one, but not more than two, of the additional radicals R at-

tached to the nuclear carbon atoms of the aromatic rings is a halogen, e. g. chlorine or bromine. The remaining radicals R are either hydrogen or lower alkyl radicals, e. g. methyl, ethyl, propyl, amyl, and the like, and these radicals R need not be identical.

Compounds of the invention represented by the Formula III above are bases and readily form acid addition salts with inorganic and organic acids, e. g. hydrochloric, hydrobromic, hydriodic, sulfuric, phosphoric, acetic, tartric, oxalic, citric, ethanesulfonic acids, and the like. They also form quaternary ammonium salts with acyclic and cyclic quaternizing agents, such as lower alkyl halides (e. g. methyl bromide, ethyl iodide, n-butyl chloride), di(lower alkyl)-sulfates (e. g. dimethyl sulfate), aralkyl halides (e. g. benzyl bromide), and the like. Since the bases of Formula III may be monoacidic or polyacidic bases, the salts formed by these bases include the mono- and poly-acid addition salts and mono- and poly-quaternary salts. The invention includes not only the bases of Formula III above, but also the acid addition salts and quaternary salts of those bases. A particularly preferred class of salts is those formed by the bases with the non-toxic acids and quaternizing agents conventionally employed in the preparation of chemotherapeutic substances.

The bases of Formula III above and their salts are useful as chemotherapeutic agents, e. g. as anthelmintic agents (for instance, in combating pinworms such as *Syphacia obvelata*); as antifungal agents (for instance in combating *Trichophyton mentagrophytes* and *Microsporon lanosum*); and as antiprotozoan agents (for instance, in combating *Trypanosoma equiperdum* and *Trichomonas vaginalis*). The compounds of this invention are administered in therapeutic dosages in conventional vehicles.

A general method for preparing the compounds of Formula III above comprises reacting a compound of the formula

wherein Z has the same meaning indicated above; and R' is a monovalent radical selected from the group consisting of hydrogen, halogen, lower alkyl, and hydroxyl; at least one, but not more than two, of the radicals R' being a hydroxyl radical and at least one, but not more than two additional of the radicals R' being a halogen with a di(lower alkyl)-amino-(lower alkyl)-halide in the presence of an acid acceptor, e. g. by heating the reactant of Formula IV together with a halide reactant in an inert organic solvent in the presence of an alkali metal alkoxide such as sodium methoxide. From the bases of Formula III, the acid addition salts and quaternary salts of the invention can be prepared, for example, by reacting the base with the appropriate acid or quaternizing agent, preferably in an organic solvent, for example, acetone, ether, etc.

The halogenated starting materials, having the Formula IV above wherein Z represents the imino group, are produced, for example, by reacting o-chloro benzoic acid or a halogen containing o-chloro benzoic acid with a primary aryl amine containing an ether group such as o-amino anisole or an amino anisole containing a halogen on the benzene nucleus. The ether group or groups on the acridone formed in this manner are converted to hydroxy groups by hydrolysis in the presence of aluminum chloride, for example. The halogenated thiaxanthones correspond-

ing to Formula IV above are produced by reacting o-mercaptop benzoic acid or a halogenated o-mercaptop benzoic acid with a halogenated ether such as p-chloro anisole. Alternatively, o-chloro benzoic acid or a halogenated o-chloro benzoic acid is condensed with a mercapto ether or halogenated mercapto ether such as 4-chloro-2-mercaptop anisole. The ether group or groups are similar converted to hydroxy groups by hydrolysis.

The following examples are illustrative of this invention. All temperatures are in degrees centigrade.

Example 1

52 grams of 1-methyl-4-hydroxy-6-chloro-9(10H)-acridone, 500 cc. of chlorobenzene, 100 cc. of methanol and 16 grams of sodium methoxide were stirred and heated to 131° until the methanol was distilled off. The reaction mixture was then cooled to 100° and 35 grams of β -diethylaminoethyl chloride were added. The mixture was refluxed for 4 hours at 130°. The reaction mixture was then cooled below 100° and 500 cc. of water and 20 cc. of sodium hydroxide (40%) were added. The mixture was then heated to 90°. The reaction mixture was then permitted to stratify. The chlorobenzene layer was separated, then dried over sodium sulfate and concentrated in vacuo. 1-methyl-4-(β -diethylaminoethoxy)-6-chloro-9(10H)-acridone crystallized in the form of slightly yellow crystals, M. P. 175-176°.

Example 2

62 grams of 1-chloro-4-hydroxy-acridone, 500 cc. of chlorobenzene, 120 cc. of methanol and 18 grams of sodium methoxide were stirred and heated to 130° and the methanol was permitted to distill off. The reaction mixture was then cooled to 100° and 45 grams of β -diethylaminoethyl chloride were added. The mixture was refluxed at 130-132° for 4 hours. The temperature was reduced to below 100° and 500 cc. of water and 25 cc. of sodium hydroxide (40%) were added. The reaction mixture was stirred for an additional hour, then permitted to stratify. The chlorobenzene layer was removed and concentrated in vacuo. The residue was extracted with 60 cc. of concentrated hydrochloric acid and 600 cc. of water on a steam bath. 5 grams of charcoal were added and the mixture was filtered while hot. The mixture was then cooled to 10° and the 1-chloro-4-(β -diethylaminoethoxy)-9(10H)-acridone was precipitated with 70 cc. of sodium hydroxide (40%). The product was crystallized from 80% alcohol. The slightly yellow crystals thus obtained melted at 115°.

Example 3

59 grams of 1-chloro-4-hydroxy-thiaxanthone, 16 grams of sodium methoxide, 500 cc. of chlorobenzene and 100 cc. of methanol were heated to 130° and the methanol was allowed to distill off. The mixture was cooled to 100° and 45 grams of β -diethylaminoethyl chloride were added. The mixture was refluxed for 4 hours at 130-132°. The temperature was then reduced to below 100° and 20 cc. of sodium hydroxide (40%) and 400 cc. of water were added. The mixture was stirred for an additional one-half hour, then allowed to stratify. The chlorobenzene layer was separated and concentrated in vacuo. The free base, 1-chloro-4-(β -diethylaminoethoxy)-thiaxanthone, was obtained as a yellow oil.

The free base obtained above was converted to the hydrochloride by dissolving it in 400 cc. of acetone. The solution was filtered and chilled to 0°. 40 cc. of ethanol-HCl (35%) were added and a light yellow crystalline precipitate formed. The light yellow, crystalline precipitate which formed was recrystallized from methanol. The monohydrochloride thus obtained melted at 227°.

36 grams of the free base obtained according to the first paragraph of this example were dissolved in 600 cc. of acetone. To this solution was added a solution of 15 grams of tartaric acid in 25 cc. of ethanol and 100 cc. of acetone. The mixture was heated to 55°. 1-chloro-4-

(β -diethylaminoethoxy) thiaxanthone monotartrate precipitated in crystalline form. Upon recrystallization from 80% alcohol, the tartrate melted at 185-187°.

Example 4

54 grams of 1,6-dichloro-4-hydroxy-acridone, 500 cc. of chlorobenzene, 15 grams of sodium methoxide and 100 cc. of methanol were heated to 132° and the methanol was allowed to distill off. 45 grams of β -diethylaminoethyl chloride were added as described in Example 3 above. The free base was isolated according to the procedure described in Example 3 and crystallized from ethanol. The light tan, crystalline 1,6 - dichloro - 4 - (β -diethylaminoethoxy)-9(10H)-acridone melted at 174-175°.

Example 5

42 grams of thiosalicylic acid and 32 grams of 4-chloro-3-methyl anisole were added to 360 grams of sulfuric acid (96%) while agitating vigorously. The mixture was stirred for four hours at 45-50°. 50 cc. of fuming sulfuric acid (5% anhydride) were added and the mixture was heated for one-half hour at 80°. The mixture was drowned in ice and water and then filtered. The 1-chloro-2-methyl-4-methoxy thiaxanthone thus obtained was hydrolyzed by refluxing with 35 grams of aluminum chloride in 250 cc. of chlorobenzene for 3 hours to obtain 1-chloro-2-methyl-4-hydroxy thiaxanthone.

28 grams of 1-chloro-2-methyl-4-hydroxy thiaxanthone, 350 cc. of chlorobenzene, 60 cc. of methanol and 9 grams of sodium methoxide were stirred and heated. The methanol was permitted to distill off. The distillation was completed when the temperature reached 131°. The mixture was cooled to 95°, 20 cc. of β -diethylaminoethyl chloride were added and the mixture was refluxed for 4 hours. Then 10 cc. of sodium hydroxide (40%) and 300 cc. of water were added at 100°. This was stirred for one-half hour, the mixture was permitted to stratify and the chlorobenzene layer was separated. The chlorobenzene extract was concentrated in vacuo. The oily 1-chloro-2-methyl-4-(β -diethylaminoethoxy)-thiaxanthone thus obtained was dissolved in 300 cc. of acetone and filtered. The filtrate was chilled to 0° and 15 cc. of ethanol-HCl (30%) were added. Crystalline 1-chloro-2-methyl-4-(β -diethylaminoethoxy)-thiaxanthone hydrochloride precipitated. Upon recrystallization from 90% ethanol, the hydrochloride melted at 240-242°.

Example 6

60 grams (0.31 mol) of the potassium salt of o-chloro benzoic acid and 52 grams (0.3 mol) of 2-chloro-4-methoxy-5-aminotoluene in 225 cc. of amyl alcohol were condensed by refluxing for 9 hours in the presence of 4.5 grams of potassium carbonate and 2 grams of copper powder.

After cooling to room temperature overnight, 30 cc. of sodium hydroxide (40%) and 600 cc. of water were added. The amyl alcohol was removed by steam distillation. The aqueous residue was filtered while hot. The filtrate was added with stirring to a mixture of ice and water containing 50 cc. of concentrated hydrochloric acid. After stirring for one-half hour, the crude condensation product was filtered off, washed acid free with cold tap water and dried under suction. The product, 2-(2-methoxy-4-chloro-5-methylanilino)benzoic acid, was recrystallized from a mixture of 1150 cc. of glacial acetic acid and 500 cc. of water, M. P. 200-202°.

65 grams (0.22 mol) of the condensation product obtained above was heated for 9 hours with 650 grams of polyphosphoric acid on a steam bath. After cooling to room temperature, the reaction mixture was carefully diluted by the dropwise addition of 800 cc. of water while cooling, and finally added to 2500 cc. of ice and water. After stirring for one hour, the crude 1-methyl-2-chloro-4-methoxy-9(10H)-acridone was filtered off, washed acid free with cold water and dried under suction. The crude

product was heated with 1000 cc. of water and 15 cc. of sodium hydroxide (40%) at 85° for one-half hour. The solid was filtered off, washed alkali free and then dried, first under suction and then in vacuo. Upon crystallization from chlorobenzene, the compound melted at 193-195°.

59 grams (0.216 mol) of 1-methyl-2-chloro-4-methoxy-9(10H)-acridone were refluxed with 95 grams of aluminum chloride in 450 cc. of chlorobenzene for 5 hours. After cooling to room temperature, the reaction mixture was carefully decomposed with crushed ice. The chlorobenzene was removed by steam distillation and the crude 1-methyl-2-chloro-4-hydroxy-9(10H)-acridone was filtered off. After dissolving in a solution of 1000 cc. of water and 100 cc. of sodium hydroxide (40%) at 85°, the product was isolated by precipitation with acetic acid and crystallized from ethanol, M. P. 312-314°.

49 grams (0.19 mol) of 1-methyl-2-chloro-4-hydroxy-9(10H)-acridone were condensed with 35 grams (0.26 mol) of β -diethylaminoethyl chloride in 600 cc. of chlorobenzene in the presence of 13 grams (0.24 mol) of sodium methoxide by refluxing for 4 hours. 150 cc. of water and 25 cc. of sodium hydroxide (40%) were then added. The reaction mixture was cooled in ice and the crystalline product which separated was filtered off. The 1-methyl-2-chloro-4-(β -diethylaminoethoxy)-9(10H)-acridone was recrystallized from ligroin-benzene, M. P. 143-145°.

The base thus obtained was converted to the hydrochloride by treatment with ethanol-HCl in benzene-ether solution. The hydrochloride was crystallized from ethyl acetate-ethanol-ether, M. P. 241-243°.

Example 7

19 grams of 1,7-dichloro-4-hydroxy-thiaxanthone (synthesized from 2-mercapto-4-chloro benzoic acid and p-chloro anisole according to the method described in Example 5), 360 cc. of chlorobenzene, 60 cc. of methanol and 6 grams of sodium methoxide were heated to 132° and the methanol was allowed to distill off. The mixture was then cooled to 100° and 15 cc. of β -diethylaminoethyl chloride were added. The mixture was refluxed for 4 hours at 130 to 132°. After cooling below 100°, 300 cc. of water and 10 cc. NaOH (40%) were added. The mixture was stirred for one-half hour then permitted to stratify. The chlorobenzene layer was separated and after drying over sodium sulfate, it was concentrated in vacuo. The oily residue, 1,7-dichloro-4-(β -diethylaminoethoxy)-thiaxanthone, was dissolved in 300 cc. of acetone and precipitated with 10 cc. ethanol-HCl containing 25% HCl. 1,7-dichloro-4-(β -diethylaminoethoxy)-thiaxanthone hydrochloride precipitated as light yellow crystals which were recrystallized from 96% aqueous alcohol, M. P. 222-224°.

Example 8

5 grams of 1-methyl-2-chloro-4-(β -diethylaminoethoxy)-9(10H)-acridone were dissolved in 50 cc. of acetone. The mixture was filtered and to the filtrate were added in the cold (10 to 15°) 10 cc. of a 25% solution of methyl bromide in acetone. Upon standing for 24 hours, 1-methyl-2-chloro-4-(β -diethylaminoethoxy)-9(10H)-acridone methyl bromide crystallized.

I claim:

1. A compound selected from the class consisting of bases having the formula

wherein Z is a bivalent radical selected from the group consisting of imino and thio, and each R is a monovalent radical selected from the group consisting of hydrogen, halogen, lower alkyl and di(lower alkyl)-amino-(lower alkoxy); at least one, but not more than two, of the radicals R being a di(lower alkyl)-amino-(lower alkoxy) radical, and at least one, but not more than two additional, of the radicals R being a halogen and salts of said bases.

2. A 9(10H)-acridone, substituted on the nuclear carbon atoms, wherein one substituent is a di(lower alkyl)-amino-(lower alkoxy) radical and a second substituent is a halogen.

3. A 9(10H)-acridone, substituted on the nuclear carbon atoms, wherein one substituent is a di(lower alkyl)-amino-(lower alkoxy) radical, a second substituent is a halogen and a third substituent is a lower alkyl radical.

4. A thiaxanthone, substituted on the nuclear carbon atoms, wherein one substituent is a di(lower alkyl)-amino-(lower alkoxy) radical and a second substituent is a halogen.

5. 1-chloro-4-(β -diethylaminoethoxy)-9(10H)-acridone.

6. 1-chloro-4-(β -diethylaminoethoxy)-thiaxanthone.

7. Acid addition salts of 1-chloro-4-(β -diethylaminoethoxy)-thiaxanthone.

8. 1-chloro-4-(β -diethylaminoethoxy)-thiaxanthone hydrochloride.

9. 1-methyl-2-chloro-4-(β -diethylaminoethoxy)-9(10H)-acridone.
